JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA

METALLIC FRAME CONSTRUCTION

Application filed July 24, 1928. Serial No. 295,035.

This invention relates to the construction of metallic frames for windows and the like, particularly to metallic frames fashioned from sheet metal.

5 The object of my invention is to expedite assembling of the component perimetric parts which go into the making of metallic frames of the kind referred to, with a view toward securing such parts rigidly and permanently together at a minimum of expense as considered both from the standpoint of labor and material costs.

How the foregoing advantages may be readily attained in practice will be manifest 15 from the detailed description which follows when taken in connection with the accompanying drawing;

Fig. I is a fragmentary elevation of the inside of a metallic window frame having its 20 perimetric components secured together in accordance with my invention, certain portions of said frame being broken away and in section to expose important details.

Figs. II and III are fragmentary top and 25 bottom plan views of the frame.

Fig. IV is a vertical sectional view of the frame, taken as indicated by the arrows IV—IV in Fig. I.

Figs. V, VI, and VII are perspective views 30 of three different types of tab pieces by aid of which the component parts of the window frame are secured together.

The window frame herein delineated comprises a head or top rail 10, a sill or bottom rail 11, and jamb or side rails whereof only 35 one is shown at 12 all components being fashioned to hollow angular cross-section from comparatively thin sheet metal after more or less common practice in this art. Each of 40 the jamb or side rails 12 is formed with a guide groove 13 for the sashes—not illustrated, and the sill or bottom rail 11 with a double step 14, against which the lower sash is adapted to close.

To secure the several described perimetric components 10, 11 and 12, of the window frame together, I provide tab pieces which 45 are respectively designated by the numerals 15, 16 and 17, in the assemblies of Figs. I—IV, and separately detailed in perspective in

Figs. V, VI and VII. As shown, the tab pieces 15, 16 and 17, are all stamped from sheet metal stock of a gage considerably heavier than that of the window frame itself.

By reference to Fig. V it will be noted that 55 the tab piece 15 is elongated and angular in form with horizontal and vertical flanges 15a, 15b, and a perpendicularly bent end or tongue projection 15x. I employ one of these pieces 15 at the top and bottom of each of 60 the side or jamb rails 12 to secure it to the head rail 10 and the sill rail 11, at the forward corner and frontal side of the window frame. As shown in Figs. I, II and III, the length of the tab piece 15 is such as to fit substantially snug within the hollow of the jamb rail 12, at the regions above designated. In placing each tab piece 15, its vertical flange 15b is butted against the frontal wall of the jamb rail 12, with the outer face of its horizontal flange 15a flush with the end edge of 65 said jamb rail, and with its tab 15x projecting therebeyond. In this position, the tab piece 15 is made fast to the jamb rail 12 preferably by spot welding its flange 15b against 70 the in side of said wall of the jamb rail.

The tab piece 16 of Fig. VI, is simply a flat oblong stamping; and I employ one such at each end of the jamb or side rail 12 to secure 75 it to the head and sill rails 10, 11, at the inner corner and at the in side of the window frame. After placement in each instance into the corner of the hollow of the jamb rail 12 at the region indicated, with a flat side 80 against the transverse jamb wall of said rail, the tab piece 16 is made fast—also preferably by spot welding—a short length being left to 85 project beyond the end of the jamb rail 12 to constitute a tongue 16x as shown in Figs. I and IV.

Like the tab piece 16, the tab piece 17 of Fig. VII is in the form of a flat stamping, but, in this instance, of irregular profile configuration, that is to say: one of its side edges is stepped as at 17a, while from its bottom edge depends a tongue 17x. From Fig. 90 IV it will be noted that the tab piece 17 is used centrally of the juncture between the jamb rail 12 and the sill rail 11 at the in or jamb side, and that it fills the width of the 95 100

sash groove 13 to the top ledge of said sill rail, with its stepped edge 17a coinciding with the stepping of the sill at 14. The tab piece 17 is likewise preferably attached by spot welding to the jamb rail 12 with the tongue 17x extending beyond the end of said rail.

At properly allocated points, the head rail 10 and the sill rail 11 are provided with apertures for reception of the tongues 15x, 16x, and 17x of the pieces 15, 16, and 17 within the ends of the jamb rails 12. After assembling the several components of the window, in the relation shown in Figs. I-IV, the tabs 15x, 16x, and 17x project through the apertures in the head and sill rails 10, 11 into the hollows of the latter where they are readily accessible for the purpose of securing them. This I effect preferably by tack or arc welding, the result of the operation being conventionally indicated in the several instances by the letters W, W' and W².

While I have specifically described my invention in connection with a metallic frame for a window, the same principle can, with attainment of like advantages, be embodied in metallic frames for other purposes. From the foregoing it will be seen, moreover, that I have provided a very simple method and means for securing together the component parts of a metallic frame with assurance of subsequent rigidity and permanence, the cost being obviously far less than in instances where screws or rivets are employed for a similar purpose.

Having thus described my invention, I claim:

1. In a metallic frame structure for windows and the like comprising top, bottom, and side rail components of hollow cross-section; angle-section tabs at opposite ends of the side rail components with perpendicular end tongue projection from the horizontal portion thereof into the top and bottom rails whereby the several rail components are permanently connectable as a rigid whole.

2. In a metallic window frame structure comprising a hollow head rail, a stepped hollow sill rail, and side jamb rails affording sash guiding grooves; tab pieces adapted to the jamb rails within the bottom ends of the sash grooves having their lower edges conforming to the stepped hollow sill with depending projections thereof extended into the hollow of said sill rail, whereby the side jamb and sill rails are rigidly and permanently connectable.

3. In a metallic window frame structure comprising a hollow head rail, a hollow sill rail, and hollow side jamb rails of angular cross-section affording sash guiding grooves; interior tab pieces of angle section laterally across the jamb rails in abutment with the outer wall thereof with vertically directed tongues projecting into the head rail; rec-

tangularly configured flat tab pieces at the inner corners of opposite ends of the jamb rails, said tab pieces embodying vertically directed tongues projecting into the hollows of the head and sill rails; and additional tab pieces having their lower edges conforming to the upper faces of the sill rail across the lower ends of the sash grooves in the jamb rails, said latter tab pieces embodying depending tongues projected into and secured within the hollow of the sill rail, and all of said tabs affording means whereby the several rails are permanently connectable into a rigid frame.

4. As an article of manufacture a tab for securing together vertical and horizontal metallic frame-structure components, said tab being of angle section material with an outstanding relatively-angled tongue integral with one of the section flange ends.

5. As an article of manufacture a tab for securing together vertical and horizontal metallic frame-structure components of irregular profile configuration with one side edge vertically stepped and having a depending tongue from the bottom edge thereof.

In testimony whereof, I have hereunto signed my name at Philadelphia, Pennsylvania, this 19 day of July 1928.

JOAH BROGDEN.
